UNITED STATES PATENT OFFICE.

PHILIP K. DEVERS, OF LYNN, MASSACHUSETTS, ASSIGNOR TO GENERAL ELECTRIC COMPANY, A CORPORATION OF NEW YORK

ELECTRICAL DISCHARGE DEVICE.

Application filed December 27, 1926. Serial No. 157,030.

The present invention relates to the class of electric discharge devices which operate by ionization of gas or vapor and in which the initially high electric resistance must be broken down, as for example, by an auxiliary discharge, before a discharge will operate between the main electrodes at the normal operating potential. It is the object of my invention to provide an improved starting arrangement.

10 In U. S. Patent 1,306,559 issued to John Orange on June 10, 1919, is described an arc device, containing electrodes supporting an arc at incandescence in mercury vapor.

15 The arc is started in an auxiliary circuit containing a body of mercury. Some of the mercury is evaporated when a starting current is caused to flow, thereby breaking the continuity of the auxiliary circuit and starting an auxiliary arc discharge which in turn starts the main discharge.

It is difficult to admit the exact amount of mercury to such a device which is required to complete the starting circuit when the device is not operating without introducing even a slight excess of mercury so that the circuit may be readily broken by evaporation of the mercury. Small globules of mercury forming by condensation on the 20 walls of the device during its operation also may unduly deplete the mercury in the starting circuit. For this reason the device may fail to restart after an interruption because the starting circuit remains open-circuited.

25 In accordance with my present invention these difficulties are overcome by providing in the envelope a small receptacle or cup suitably positioned with respect to the starting circuit and in which sufficient and definite amount of mercury may be introduced to positively complete the starting circuit. By properly proportioning and positioning this receptacle, the amount of mercury thus introduced into the starting circuit can be 30 restricted to an amount which will not unduly delay the starting of the arc.

35 My invention is illustrated in the accompanying drawing in which Fig. 1 is a side view of my improved device prior to starting the arc (the main envelope being shown in part broken away); and Fig. 2 is a side view of the device after operation.

40 Referring to the drawing, the device comprises an envelope 1 consisting of glass, 45 quartz or other suitable material. Sealed

therein are stems or wires 2, 3 consisting of tungsten, molybdenum or other suitable metal. The ends 4, 5 of these stems, which preferably are reduced in section as shown in Fig. 1 terminate in electrodes 6, 7 consisting of tungsten or other suitable refractory material, these electrodes being separated by a gap having a length of 15 to 500 mils, depending on the character of the device. The space within the envelope may be evacuated or charged with a suitable gas, such as nitrogen, hydrogen, a rare gas, such as argon, or a mixture of gases. There also is contained therein a quantity 8 of mercury, or other suitable normally liquid, easily 50 vaporizable material. Depending from the conductors 4, 5 and joined thereto as by fusion, are small spiral conductors 10, 11 which terminate in electrode-like enlargements or terminals 12, 13. These terminals 55 12, 13 project into a cup 14, which preferably consists of silica and which is affixed to the envelope 1 at 15. In a 200 watt device the main electrodes 6, 7 may have a diameter of about 100 mils. The coils 10, 11 may consist of 18 mil wire wound on a 40 mil mandrel and may have 8 to 10 turns.

When it is desired to start an arc between the main electrodes 6, 7 a globule of mercury 16 is introduced into the cup 14 by 60 shaking or tilting the device. Thereby completing the starting circuit, current is caused to flow in the starting circuit evaporating some of the mercury and again breaking the circuit and starting an arc which 65 travels up the coils and establishes an arc between the main electrodes. The resistance of the coils is chosen to be greater than the resistance of the main discharge path. Consequently the starting of the main discharge 70 is prompt and positive. When the mercury globule 16 is removed by evaporation from the cup 14 it lodges in the space between the cup and the envelope 1 and hence can not interfere with the steady operation on the 75 arc.

What I claim as new and desire to secure by Letters Patent of the United States, is:

1. An electric discharge device comprising an envelope, cooperating spaced electrodes 80 therein, a starting circuit therefor, a quantity of normally liquid vaporizable conducting material in said envelope, and a receptacle within said envelope located and shaped to contain a quantity of said vaporiz- 85

able material in position to close said starting circuit.

2. An electric discharge device comprising an envelope, cooperating fixed electrodes therein constituted of substantially non-vaporizable material, a normally incomplete starting circuit therefor, a quantity of mercury in said envelope, and means in said envelope facilitating the introduction into said starting circuit of a definite amount of mercury to complete said starting circuit.
3. An electric discharge device comprising an elongated envelope, conducting stems sealed into one end of said envelope and extending to a region adjacent the opposite end

of said envelope, electrodes affixed to said stems, and positioned so spaced apart that an arc may be operated therebetween, arc-starting conductors respectively affixed at one end to said stems and separated at their opposite ends by a gap, a cup affixed to said envelope adjacent the separated ends of said conductors and a sufficient quantity of mercury in said envelope to enable the gap between said arc starting conductors to be closed thereby in said cup.

In witness whereof, I have hereunto set my hand this twenty-first day of December, 1926.

PHILIP K. DEVERS.
